UNITED STATES PATENT OFFICE.

CHARLES H. GUTMANN, OF MOUNT VERNON, NEW YORK, ASSIGNOR TO LAZARUS & ROSENFELD, A COPARTNERSHIP DOING BUSINESS IN NEW YORK, N. Y.

DESIGN FOR A CANDLESTICK.

46,124.

Specification for Design.

Patented July 21, 1914.

Application filed March 28, 1914. Serial No. 828,082. Term of patent 7 years.

To all whom it may concern:

Be it known that I, CHARLES H. GUTMANN, a citizen of the United States, residing at Mount Vernon, in the county of Westchester and State of New York, have invented a new, original and ornamental Design for a Candlestick, of which the following is a specification, reference being had to the accompanying drawing, forming a part thereof.

Referring to the drawing, Figure 1 is a plan view of the candle stick showing my design, and Fig. 2 is an elevation thereof.

I claim:

The ornamental design for a candle stick as shown.

CHARLES H. GUTMANN.

Witnesses:

GEORGE L. THOM,
MAE PERRY.
